SHOE AND PROCESS OF MAKING THE SAME

John J. Walsh, Des Peres, Mo., assignor to Charles D. P. Hamilton, Jr., Charles D. P. Hamilton, III, Everett R. Hamilton, Forest Ross Hamilton, Albert J. Scheu, and John J. Walsh, a partnership doing business under the trade-name Penaljo Company, St. Louis, Mo.

Application March 25, 1944, Serial No. 528,078

3 Claims. (Cl. 12—142)

1

This invention relates to a new and useful improvement in shoes and to the process of making the same.

My invention has for its primary object the provision of a shoe requiring for its production only a few process operations which are readily effected with ease, accuracy, and precision by relatively unskilled workers and with consequent savings in labor costs and the elimination of losses by reason of faulty and rejected shoes.

My invention has for a further object the provision of a shoe through and by the employment of the process-operations mentioned which is simple and sturdy in structure, which is soft and comfortable on the foot, which is light in weight and attractive in appearance, and which is efficiently serviceable.

And with the above and other objects in view, my invention resides in the novel features of form, construction, arrangement, and combination of parts and in the unique steps or process of shoe production all presently described and pointed out in the claims.

In the accompanying drawings (two sheets):

Figures 1 to 5, both inclusive, illustrate in plan or perspective some of the elements, namely, the insole-cover, the upper, and the insole, employed in the construction, and forming part, of a shoe of my invention;

Figure 6 illustrates the insole of Figure 5 as partially marginally skived on its under face and equipped with a so-called shank-stiffener, as embodied in the finished shoe;

Figure 7 is an enlarged longitudinal sectional view of the shank-stiffener-equipped and marginally skived insole of Figure 6;

Figure 8 illustrates in perspective the upper of Figure 4 marginally joined to the marginally nicked insole-cover of Figure 2 for connection, in turn, as a unit with the insole of Figures 6 and 7;

Figures 9 to 15, both inclusive, illustrate the several successive process-steps involved in joining the connected upper and insole-cover of Figure 8 with the insole of Figure 7;

Figure 16 is an inverted, partly broken plan view of the partially finished shoe;

Figure 17 is a reduced side elevational view of a finished shoe constructed in accordance with and embodying my invention; and

Figure 18 is a transverse sectional view of the finished shoe taken approximately on the line 18—18, Figure 17.

Referring now more in detail and by reference characters to the accompanying drawings, which are illustrative both of a practical embodiment of a shoe of my present invention and of its method or process of manufacture or production, the present shoe is built up on a so-called covered insole as a foundation, as it may be said, without the employment or use, during the first steps of its production, of a last.

2

To such end, I provide a section or piece A of cloth, thin leather, or other readily or easily flexible fabric or material cut to and having the general outline or contour and dimensions of the outer sole of the particular shoe being manufactured, as is best seen in Figure 1.

Such material-section A becomes, as presently appearing and as it may now be designated, the shoe-insole cover, and to facilitate subsequent marginal underfolding of the insole-cover A on and about the shoe-insole, the cover A is preferably nicked or notched, as at 1, around the heel, the toe, and at the base of the ball and at other selected points along its margin, as shown in Figure 2.

Depending then upon the desired size and contour of the particular shoe, the insole-cover A is suitably, either by an operator or worker or otherwise, marked or indexed, as at 2, 2, throughout, for the most part, its shank and ball-portion and in suitable adjacency to its margin, as shown in Figure 3, so as to afford or provide not only a visual pattern for indicating to the operator the line of attachment in subsequently sewing or stitching the upper B, Figure 4, to the insole-cover A, but also a marginal portion 3 for insole underfolding, as presently appears.

The upper B, Figure 4, is first cut and otherwise constructed to approximately conform to the contour, shape, and size required in the finished shoe. Such upper B will, of course, comprise any suitable marginally flexible material and may, while in the present instance illustrated as of the open heel and open toe type, shape, or design, equally well be of closed heel and closed toe or other desired or selected type, shape, or design, and suitably surface embellished or ornamented. Suffice now merely to say that, as shown in Figure 8, the particular upper B is preferably by lines of thread-stitches 4 projected vertically or at right angles, as it may be said, through the cover A and upper B stitched at and along its lower opposite side margins 5, 5, to, and along the indicated or pattern stitch-line 2 of, the insole-cover A. Thus, I provide, as a unit, the combined insole-cover and upper illustrated in Figure 8 for incorporation, as soon appears, in the finished shoe.

C designates an insole of any approved or standard type, which, as is customary, includes a heel and shank-portion 6 of fiber or other relatively stiff or rigid material lengthwise arcuated or curved, as best seen in Figure 7, to conform to the arch of the foot and equipped with a fore-part or ball-portion 7 of thin fiber-board or other suitable flexible or pliable material and equipped centrally and longitudinally on its under face with a suitable and correspondingly lengthwise curved shank-stiffener 8 of metal or other suitable rigid material. It will be understood, of course, that the insole C is approximately of the

precise size and contour of the finished shoe and is then disposed flatwise, as indicated in Figures 9 and 10, on the preferably adhesively coated under face of the insole-cover A and to which cover A the insole C is adhesively or otherwise permanently fixed throughout from toe to heel, as indicated in Figure 10.

With the parts A, B, and C so joined or united one to the other, preferably only that part of the marginal portion 3 of the insole-cover A which extends from and around the heel to the base of the ball thereof is suitably coated with adhesive, as indicated in Figure 11, and then turned or folded under and adhesively fixed flatwise to and upon the corresponding marginal portion of the insole C, as is indicated in Figure 12, such underfolding being facilitated by the marginal nicks or notches 1.

A last D of the proper size and contour, depending upon the desired size, contour, and shape of the finished shoe, is then disposed within the upper B and upon the upper face of the insole-cover A, as shown in Figure 13, such disposition of the last D being greatly facilitated by the fact that the upper B, as stitched or united to the insole cover A, is, as it may be said, initially somewhat oversize, and then, to insure subsequent precise lasting, tacks or other temporary securing members 9 are preferably disposed through the insole C and insole-cover A and into the last D, as indicated in Figure 14.

With the last D so disposed in co-operative relation to the joined insole-cover A, upper B, and insole C, the remaining part of the marginal portion 3 of the insole-cover A is on its under face equipped or coated with suitable adhesive, as also indicated in Figure 14, and is then with the attached marginal portions of the upper B pulled around and folded under and preferably adhesively fixed to and upon the corresponding marginal portion of the insole C, such underfolding of the marginal insole-cover portion 3 being again facilitated by marginal nicks or notches 1 and lasting the upper B to approximately the precise fit required or desired in the finished shoe E illustrated in Figure 17. When so underfolded, the marginal portion not only of the cover, but also of the upper are concealed between the outer sole and insole.

The temporary securing tacks 9 are thereupon removed, and an outer sole F of the desired shoe-contour, design, and shape is then adhesively or otherwise suitably fixed flatwise to and upon the under face of the insole C and over, and thereby concealing, the underfolded marginal portions of the insole-cover A and upper B, as is best seen in Figures 16 and 18.

It will be understood, of course, that the shoe-parts or elements are permitted to stand from time to time during the production of the shoe to allow the adhesive or cementitious binding or securing material to dry and harden, and in due course a heel G is suitably affixed at the desired location to and upon the under face of the outer sole F, when the finished shoe E illustrated in Figure 17 results, a shoe which, in production and in form, fit, and appearance meets and fulfills the objects stated.

I may add that, if the upper of the particular shoe be of the closed heel and closed toe type, as indicated in dash-lines in Figure 17, the particular upper will throughout its margin be correspondingly stitched to the insole-cover A, as indicated by dash-lines in Figure 3, so as to provide

a flexible marginal portion throughout for insole underfolding, and it is to be understood that other changes and modifications in the form, construction, arrangement, and combination of the several parts of the shoe, as well as changes also in its steps of manufacture or production, may be made and substituted for those herein shown and described without departing from the nature and principle of my invention.

Having thus described my invention, what I claim and desire to secure by Letters Patent is:

1. That process of shoe production which includes the provision of an insole-cover having approximately the contour of the finished shoe, providing an upper also having the approximate dimensions and shape desired in the finished shoe, then securing the upper marginally to, and upon the upper face and at a selected distance from the outer edge of, the cover for joining the cover and upper and providing a marginal portion for insole underfolding, then disposing an insole to and upon the under face of the insole-cover, then underfolding and securing said marginal cover portion and upper portion partially to and upon the under face of the insole, disposing a last within the upper and upon the cover, and then pulling and folding the remaining part of said upper and cover marginal portion under and securing the same to the insole.

2. That process of shoe production which includes the provision of an insole-cover having approximately the contour of the finished shoe, providing an upper also having the approximate dimensions and shape desired in the finished shoe, then securing the upper marginally to, and upon the upper face and at a selected distance from the outer edge of, the cover for joining the cover and upper and providing a marginal portion for insole underfolding, then disposing an insole to and upon the under face of the insole-cover, then underfolding and securing said marginal cover portion and upper portion partially to and upon the under face of the insole, disposing a last within the upper and upon the cover, then pulling and folding the remaining part of said upper and cover marginal portion under and securing the same to the insole, and then securing an outer sole to and upon the outer face of the insole in such manner as to conceal therebetween the underfolded marginal portions of the insole-cover and upper.

3. The process of making a shoe which includes the provision of an insole cover having approximately the contour of the finished shoe, cutting a plurality of spaced slits for a short distance radially inwardly from the peripheral margin of the cover along those portions of its length which lie in the region of the ball portion of the shoe when finished, providing an upper also having the approximate dimensions and shape desired in the finished shoe, securing the upper marginally to and upon the upper face of the cover at a selected distance from the outer edge thereof by a line of stitches spaced inwardly from the internal ends of said slits, adhesively joining the cover to an insole, disposing a last within the upper and upon the cover, folding the marginal edges of the cover together with the marginal edges of the upper secured thereto over and around the peripheral edge of the insole, and finally securing an outer sole upon the under face of the inner sole and against the undeturned marginal portions of the cover and upper.

JOHN J. WALSH
